(57) **CLAIM**

The ornamental design for a casing for electronic equipment, as shown and described.

DESCRIPTION

FIG. 1 is a perspective view of a first embodiment of a casing for electronic equipment.

FIG. 2 is a top view of the casing for electronic equipment of FIG. 1. The bottom view is substantively identical to the top view.

FIG. 3 is a front view of the casing for electronic equipment of FIG. 1. The rear view is substantively identical to the front view.

FIG. 4 is a right side view of the casing for electronic equipment of FIG. 1. The left side view is substantively identical to the right side view.

FIG. 5 is a perspective view of a second embodiment of a casing for electronic equipment.

FIG. 6 is a top view of the casing for electronic equipment of FIG. 5. The bottom view is substantively identical to the top view.

FIG. 7 is a front view of the casing for electronic equipment of FIG. 5. The rear view is substantively identical to the front view.

FIG. 8 is a right side view of the casing for electronic equipment of FIG. 5. The left side view is substantively identical to the right side view.

FIG. 9 is a perspective view of a third embodiment of a casing for electronic equipment.

FIG. 10 is a top view of the casing for electronic equipment of FIG. 9. The bottom view is substantively identical to the top view.

FIG. 11 is a front view of the casing for electronic equipment of FIG. 9. The rear view is substantively identical to the front view.

FIG. 12 is a right side view of the casing for electronic equipment of FIG. 9. The left side view is substantively identical to the right side view.

FIG. 13 is a perspective view of a fourth embodiment of a casing for electronic equipment.

FIG. 14 is a top view of the casing for electronic equipment of FIG. 13. The bottom view is substantively identical to the top view.

FIG. 15 is a front view of the casing for electronic equipment of FIG. 13. The rear view is substantively identical to the front view.

FIG. 16 is a right side view of the casing for electronic equipment of FIG. 13. The left side view is substantively identical to the right side view.

(Continued)

FIG. 17 is a perspective view of a fifth embodiment of a casing for electronic equipment.

FIG. 18 is a top view of the casing for electronic equipment of FIG. 17. The bottom view is substantively identical to the top view.

FIG. 19 is a front view of the casing for electronic equipment of FIG. 17. The rear view is substantively identical to the front view.

FIG. 20 is a right side view of the casing for electronic equipment of FIG. 17. The left side view is substantively identical to the right side view.

FIG. 21 is a perspective view of a sixth embodiment of a casing for electronic equipment.

FIG. 22 is a top view of the casing for electronic equipment of FIG. 21. The bottom view is substantively identical to the top view.

FIG. 23 is a front view of the casing for electronic equipment of FIG. 21. The rear view is substantively identical to the front view; and,

FIG. 24 is a right side view of the casing for electronic equipment of FIG. 21. The left side view is substantively identical to the right side view.

The portions of the casing for electronic equipment shown in broken lines form no part of the claimed design.

1 Claim, 18 Drawing Sheets
